United States Patent Office

Des. 227,167
Patented June 5, 1973

227,167

DATA RECORDER

John A. Maul, Cuyahoga County, Ohio, assignor to
Addressograph-Multigraph Corporation, Cleveland,
Ohio

Filed May 28, 1971, Ser. No. 148,301

Term of patent 14 years

Int. Cl. D18—02

U.S. Cl. D64—11

Fig.4

Fig.5

FIG. 1 is a left side and top perspective view of a data recorder showing my new design;

FIG. 2 is a front elevational view thereof;

FIG. 3 is a rear elevational view thereof;

FIG. 4 is a right side elevational view thereof; and

FIG. 5 is a top plan view thereof.

I claim:

The ornamental design for a data recorder, substantially as shown.
